UNITED STATES PATENT OFFICE

169,473

AISLE STANDARD FOR RECLINING CHAIRS

Laurence W. Brulin, New York, N. Y., and Laird F. Covey, Darien, Conn., assignors to American Seating Company, Grand Rapids, Mich., a corporation of New Jersey

Application October 23, 1952, Serial No. 21,958

Term of patent 14 years

(Cl. D15—8)

To all whom it may concern:

Be it known that we, Laurence W. Brulin and Laird F. Covey, citizens of the United States and residents, respectively, of New York, in the county of New York and State of New York, and Darien, in the county of Fairfield and State of Connecticut, have invented a new, original, and ornamental Design for an Aisle Standard for Reclining Chairs, of which the following is a specification, reference being had to the accompanying drawing, forming a part thereof.

Figure 1 is a front perspective view of an aisle standard for reclining chairs, showing our new design, the reclining chairs being indicated in broken lines for illustrative purposes only.

Figure 2 is a rear perspective view of the same.

We claim:

The ornamental design for an aisle standard for reclining chairs, substantially as shown and described.

LAURENCE W. BRULIN.
LAIRD F. COVEY.
